(57) CLAIM

The ornamental design for a bottle, as shown.

DESCRIPTION

FIG. 1 is a front elevation view of a bottle showing my new design, the rear elevation view being identical;

FIG. 2 is a top plan view thereof; and,

FIG. 3 is a bottom plan view thereof.

The bottom unclaimed details have not been shown through the transparent surface in FIG. 2 for ease of illustration.

The broken lines shown in the drawings represent unclaimed environment and are for illustrative purposes only, forming no part of the claimed design.
